UNITED STATES PATENT OFFICE

ROSCOE A. HEAD, OF CEDAR VALE, KANSAS

BUNDLE HOLDER FOR CORN BINDERS

Application filed October 31, 1928. Serial No. 316,180.

The present invention relates to a bundle holder for corn binders and aims to provide a structure which will hold the bundle upright so that the top of the bundle will not lean over while the packers of the binder are making a bundle and to release the bundle out on the carrier of the binder after the bundle has been completed.

Another aim of the invention is to provide a bundle holder of this nature which is exceedingly simple in its construction, easy to install on the binder, adjustable, thoroughly efficient and reliable in use and operation, strong and durable, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a fragmentary illustration of a corn binder showing the rear end thereof in side elevation,

Figure 2 is a perspective view of a bolt for pivotal engagement with the bundle engaging member,

Figure 3 is a perspective view of a curved bolt for association with the bundle engaging member,

Figure 4 is a rear elevation of the bundle holder,

Figure 5 is a side elevation thereof,

Figure 6 is a perspective view of the lower supporting arm,

Figure 7 is a perspective view of the frame,

Figure 8 is a sectional view taken substantially on the line 8—8 of Figure 4,

Figure 9 is a sectional view taken substantially on the line 9—9 of Figure 4,

Figure 10 is a perspective view of the bundle engaging member,

Figure 11 is a perspective view of the bracket arm.

Referring to the drawing in detail, it will be seen that the numeral 5 denotes a bar which is bolted as at 6 and 7 to the upper end of a

needle chain platform 8. Apertures 9 are provided in the bar 5 for receiving the bolt 6 while a slot 10 is provided for receiving the bolt 7 so that obvious adjustment may be made.

The rear end of the bar 5 is provided with an upstanding extension 11 with an opening 12 therein. The numeral 14 denotes the bundle holder frame which is in the form of a vertical bar having a forwardly and downwardly inclined extension 15. The extension 15 is provided with a plurality of apertures 16 and the slot 17 so that the same may be bolted under the upper feed chain board of the binder by bolts 18 and 19 respectively, passing through openings 16 and slot 17 so that obvious adjustments may be made.

The inclination of the extension 15 is controlled obviously by the inclination of the upper feed chain board 20 of the binder as is clearly apparent from Figure 1. A bracket 21 is provided with an oblong sleeve 22 at one end circumjacent the frame 14 to be belted thereto by a bolt 23 passing through anyone of a series of openings 24 in accordance with the height of the bundles.

This bracket extends laterally of the binder and terminates in a forwardly directed extension 25 having an opening 26 therein. A bolt 27 is slidable through the opening 26 and has a spring 28 thereabout impinged against the extension 25 and the head of the bolt. The letter B denotes a bundle engaging member which is formed of two bars having intermediate portions 30 riveted or otherwise secured together as at 31 and the forward ends of these intermediate portions diverge forwardly from each other and merge into coextensive parallel bundle engaging fingers 32.

The rear ends of the portions 30 diverge rearwardly from each other as at 33 and terminate in spaced parallel coextensive portions 34 the rear ends of which are pivotally engaged with the forward end of the bolt 27 as is indicated at 35.

A curved bolt 36 extends through one of the openings 37 in the bracket 21 and has a pin 38 in the adjacent extremity thereof. This curved bolt extends between the rear

portions 34 of the bundle engaging member B. A buffer spring 40 is disposed about the bolt between portions 34 and the bracket 21.

5 A spring 41 is disposed about the bolt between portions 34 and a nut 42 on the end of the bolt. The bolt 36 will be engaged in the opening 37 adjacent the frame 14 for extra heavy bundles.

With this bundle holder in place it will be
10 seen that the bundles being formed in the
binder will be held in an upright position
so that the tops thereof will not lean over
while the packers are in the operation of making
15 the bundles. When the packers have completed
their work and the binder trips the
bundle the spring 41 allows the member B to
swing to the dotted line position clearly illustrated
20 in Figure 4 and bolt 27 assumes the position
also shown in Figure 8. These springs 41 and 28 will tend to return the member B to its normal position and the spring 40 will function as a buffer in its return.

It is thought that the construction, operation,
25 utility and advantages of this invention
will now be quite apparent to those skilled in
this art without a more detailed description
thereof.

The present embodiment of the invention
has been disclosed in considerable detail
30 merely for the purposes of exemplification,
since in actual practice it attains the features
of advantage enumerated as desirable in the
statement of the invention and the above description.

35 Having thus described my invention, what
I claim as new is:

1. A bundle holder for binders of the class
described including, in combination, a frame,
40 a bracket adjustably mounted on the frame
and extending laterally therefrom, a curved
bolt fixed to the bracket and extending therefrom,
said bracket having an offset end with
45 an opening therein, a bolt extending through
the opening, a spring on the second mentioned
bolt between the head thereof and the extension,
a bundle engaging member having portions
50 straddling the first mentioned bolt and
having an end pivotally engaged with the second
mentioned bolt, a spring on the first mentioned
bolt urging the bundle engaging member into
engaging position.

2. A bundle holder for binders of the class
described including, in combination, a frame,
55 a bracket adjustably mounted on the frame
and extending laterally therefrom, a curved
bolt fixed to the bracket and extending therefrom,
said bracket having an offset end with
60 an opening therein, a bolt extending through
the opening, a spring on the second mentioned
bolt between the head thereof and the extension,
a bundle engaging member having portions
65 straddling the first mentioned bolt and
having an end pivotally engaged with the second
mentioned bolt, a spring on the first mentioned
bolt urging the bundle engaging

member into engaging position, a second
spring on the first mentioned bolt between
the bundle engaging member and the bracket.

3. A bundle holder for binders of the class
described including, in combination, a frame,
70 a bracket adjustably mounted on the frame
and extending laterally therefrom, a curved
bolt fixed to the bracket and extending therefrom,
said bracket having an offset end with
75 an opening therein, a bolt extending through
the opening, a spring on the second mentioned
bolt between the head thereof and the extension,
a bundle engaging member having portions
80 straddling the first mentioned bolt and
having an end pivotally engaged with the second
mentioned bolt, a spring on the first mentioned bolt between the
bundle engaging member and the bracket, said
85 frame having an extension at its upper end inclining
downwardly and forwardly for attachment
under the upper feed chain bore of the binder,
a bracket arm adjustably mounted on the lower end of the frame for engagement
90 with the needle chain bore of the binder.

4. A bundle holder mechanism of the class
described including, in combination, a supporting
95 structure, a bolt slidable in the supporting
structure, a bundle engaging member pivotally engaged with the bolt, a head on the bolt remote from the bundle holder, a spring on the bolt impinging against the head of the bolt and the supporting structure, a second bolt in the supporting structure, a spring thereon impinging against the bundle
100 engaging member to hold it in a predetermined normal position.

In testimony whereof I affix my signature.
ROSCOE A. HEAD.
